The ornamental design for a portable base for a post support sign, as shown and described.

DESCRIPTION

FIG. 1 is a front perspective view of a portable base for a post supported sign embodying our invention;

FIG. 2 is a rear perspective view thereof;

FIG. 3 is a bottom plan view thereof; and,

FIG. 4 is a side elevational view thereof, the opposite side view being a mirror image.

FIG. 1

FIG. 2
